GIUSEPPE DE MERCURIO, OF HAMMONTON, NEW JERSEY.

WINDOW CONSTRUCTION.

Application filed February 2, 1928. Serial No. 251,369.

This invention relates to window constructions, and has more particular reference to an improved construction of that type wherein vertically sliding sashes are so mounted as 5 to be readily swung inwardly and downwardly so that convenient access may be had thereto for cleaning and repair.

The primary object of the present invention is to provide a sash construction of the 10 above type which is extremely simple and durable in construction as well as efficient and reliable in use.

A more particular object is to provide an improved sash construction of the above kind 15 in which a main outer window frame section is provided for being fixed in the opening of a building wall, and in which an inner supplemental frame section carries vertically 20 slideable sashes and is hinged at its lower end to the main outer frame section for swinging vertically into or out of the latter, the inner supplemental frame section being provided with sash weight guides at the sides thereof so that disconnection of the sash 25 cords from the sash weights is rendered unnecessary when the inner supplemental frame section is swung inwardly and downwardly to provide for convenient access to the sashes.

Still another object is to provide a window 30 construction of the above kind in which a simple and efficient counter-balancing means is provided for the swinging inner supplemental frame section, whereby the latter may 35 be swung into or out of the outer main frame section with the expenditure of a minimum amount of effort, and whereby the inner supplemental frame section may be adjusted to any desired inwardly and downwardly 40 swung position.

Other objects will become apparent as the 45 nature of the invention is better understood, and the same consist in the novel form, combination and arrangement of parts herein- 50 after more fully described, shown in the accompanying drawing and claimed.

In the drawing:

Figure 1 is an inside elevational view of 55 a window construction embodying the present invention with the inner supplemental frame section in its normal upwardly swung operative position within the main outer frame section;

Figure 2 is a side elevational view thereof, 55 partly broken away and in section, and with the inner supplemental frame section swung

inwardly and downwardly to facilitate access to the sashes; and

Figure 3 is an enlarged fragmentary vertical section taken substantially upon line 60 3-3 of Figure 2.

Referring more in detail to the drawing, the present invention embodies a main outer frame section having a top wall 5, side walls 6, a front wall 7 and a sill 8 provided with 65 an inner projecting part 9. The main outer frame section is thus open at the rear, and hinged at its lower end and adjacent its inner side, as at 10, to the projecting inner part 9 of the sill 8 is a supplemental inner 70 frame section comprising side walls 11 rigidly connected at the top by a wall 12 and having a pair of inner grooves 13 defined by a parting strip 14 and inner and outer jambs 15 and 16 and in which the upper and lower 75 sashes 17 and 18 are respectively vertically 80 slideable. The inner frame section is thus mounted at its lower end to swing vertically upon a horizontal axis upwardly and outwardly into or downwardly and inwardly 85 out of the main outer frame section, and it will be seen that when the inner supplemental frame section is swung inwardly and downwardly to a substantially horizontal position as shown in Figure 2, the sashes will 90 be readily accessible for cleaning or repair.

Mounted in openings provided in the upper end portions of the side members 11 of the inner supplemental frame section, coincident with the guide grooves 13, are suitable guides or pulleys 19 over which the sash cords 20 pass, the inner ends of the sash cords being suitably attached to the sides of the sashes 17 and 18 near the tops of the latter as is generally well known in the art, 95 and the outer ends of the sash cords being attached to suitable sash weights 21 disposed at the outer sides of the walls 11 and freely vertically movable in the respective guideways 22 of hollow partitioned guides 100 23 fixed to the side walls 11 of the inner frame section. It will thus be seen that the guides and sash weights will swing inwardly and downwardly with the inner frame section so that disconnection of the sash cords 105 from the sash weights is rendered unnecessary when positioning the inner frame section to have ready access to the sashes. The guides 23 preferably terminate at their upper ends directly below the guides or pulleys 19 110 so that access may be had to the sash cords and sash weights whenever desired. Fur-

ther, the guides 23 are preferably in the nature of metallic members suitably fastened to the wooden side walls 11 so as to be capable of removal when required. It will be noted that the front or outer wall 7 of the main outer frame section projects inwardly of the walls 5 and 6 so as to provide an abutment for and conceal the guides 23 when the inner supplemental frame section is in its upwardly swung position. The inner supplemental frame section further has an inner wall 24 which projects outwardly of the walls 11 and 12 to abut the inner edges of the walls 5 and 6 when the inner frame section is in its upwardly swung position, the wall 24 being located at the inner sides of the guides 23. Thus, when the inner supplemental frame section is in its upwardly swung position, a finished and neat appearing window frame construction is had which may of course be made to appear as an ordinary window construction when the hinges 10 are suitably concealed or employed in a relatively small and ornamental form. The hinges 10 being located at the forward or outer portion of the projecting part 9, the latter will form an abutment for limiting the downward swinging movement of the inner frame section as shown in Figure 30 2, to a horizontal position.

The inner frame section is of a height so that its top wall 12 will normally be located spaced below the top wall 5 of the outer frame section, and mounted horizontally within this space of the main outer frame section is a conventional spring roller 25 similar to rollers commonly used for window shades, with the pawls and ratchets removed. A flexible member or cord 26 is attached intermediate its ends to the central part of the spring roller 25 and has its ends attached as at 27 to the top wall 12 of the inner frame section adjacent the sides of the latter. The spring roller 25 is so mounted that when the inner frame section is swung inwardly and downwardly to unwind the cord portions or strands of the cord 26 therefrom, its spring is placed under tension, the tension being relieved by the winding of the cord strands thereon when the inner frame section is swung upwardly and outwardly. In this way the inner frame section is effectively balanced so that a minimum amount of effort is required in swinging the inner frame section to and from its operative position within the outer main frame section. Further, this construction will permit the inner frame section to be left at any desired adjustment between its limits of swinging movement. As shown, the pintles at the ends of the roller 25 are engaged with suitable supporting brackets 28 mounted on the inner side of the front wall 7 directly beneath the top wall 5. A suitable hasp 29 may be provided upon the

free edge of the inner wall 24 of the inner frame section at one side of the latter in position to engage a keeper 30 carried by the adjacent side wall 6 of the outer frame section when the inner frame section is swung to its normal operative position within the main frame section of the window. This will releasably hold the inner frame section in its normal position in an obvious manner. As the construction at both sides of the frame is the same, the construction at only one side is illustrated in the drawing and it is believed that this will be sufficient to enable a clear understanding of the invention. In other words, the sash cords, sash cord guides, sash weights and sash weight guides are provided at each side of the window frame in the manner illustrated with respect to one side in the drawing.

Minor changes may be made without departing from the spirit and scope of the invention as claimed.

What I claim as new is:—

1. In combination, a main stationary outer window frame section, a supplemental inner window frame section having upper and lower window sashes vertically slidable therein and hinged at its lower end to the bottom of the outer frame section to swing inwardly and downwardly out of the latter, and balancing means for the sashes carried by said inner frame section. 90

2. In combination, a main stationary outer window frame section, a supplemental inner window frame section having upper and lower window sashes vertically slidable therein and hinged at its lower end to the bottom of the outer frame section to swing inwardly and downwardly out of the latter, balancing means for the sashes carried by said inner frame section, and balancing means for said inner frame section. 100

3. In combination, a main stationary outer window frame section, a supplemental inner window frame section having upper and lower window sashes vertically slidable therein and hinged at its lower end to the bottom of the outer frame section to swing inwardly and downwardly out of the latter, balancing means for the sashes carried by said inner frame section, balancing means for said inner frame section, and embodying a spring roller mounted in the top of the outer frame section, and a flexible member attached to said spring roller and connected to the top of the inner frame section. 110

4. In combination, a main stationary outer window frame section, a supplemental inner window frame section having upper and lower window sashes vertically slidable therein and hinged at its lower end to the bottom of the outer frame section to swing inwardly and downwardly out of the latter, balancing means for the sashes carried by said frame section, and means to releasably 125

hold the inner frame section in upwardly and outwardly swung position within the outer frame section.

5. In combination, a main stationary outer window frame section, a supplemental inner window frame section having upper and lower window sashes vertically slidable therein and hinged at its lower end to the bottom of the outer frame section to swing inwardly and downwardly out of the latter, balancing means for the sashes carried by said inner frame section, and embodying partitioned sash weight guides attached to the sides of the inner frame section, sash 10 cord guides mounted in the upper portion of the sides of said inner frame section, sash weights vertically slidable in said sash weight guides, and sash cords attached to the sides of the sashes extending over said 15 20 sash cord guides and attached to said sash weights.

6. In combination, a main stationary outer window frame section, a supplemental inner window frame section having upper and lower window sashes vertically slidable therein and hinged at its lower end to the 25

bottom of the outer frame section to swing inwardly and downwardly out of the latter, and balancing means for the sashes carried by said inner frame section, said outer frame section having a sill provided with an inner projecting part forming a stop abutment to limit the inward and downward swinging movement of the inner frame section to a substantially horizontal position. 30 35

7. A window structure comprising a rectangular open frame to fill a wall opening, and a sash holding frame fitting within said wall opening and hinged to the lower part of said open frame, whereby it may be 40 swung inwardly to a horizontal or inclined position, upper and lower sashes mounted in said inner frame, cords carrying sash balancing weights attached to said sashes, partitioned guide ways for the weights attached 45 to the sides of said inner frame, the said inner frame being movable on its hinges with both upper and lower sashes carried thereby.

In testimony whereof I affix my signature.

GIUSEPPE DE MERCURIO.
